Research Corporation, San Francisco, Calif., a
corporation of Delaware

Application August 8, 1945, Serial No. 609,676

8 Claims. (CL 196—14.19)

1

This invention relates to refinement of petroleum distillate oils and more particularly to the refinement of lamp oils and distillate fuels containing appreciable amounts of aromatic or unsaturated hydrocarbons and sulfur compounds.

It is an object of this invention to refine petroleum fractions for the production of lamp oils, fuel oils and similar products composed of relatively more paraffinic and naphthenic hydrocarbons substantially free of aromatic and unsaturated hydrocarbons, and containing only small amounts of such impurities as sulfur compounds, nitrogen compounds, phenols, naphthenic acids, asphaltic substances and inorganic matter.

Another object of the invention is to provide a process for the extraction of aromatic and olefin type hydrocarbons and sulfur containing components from petroleum distillate fractions by extracting said fraction with sulfur dioxide, and then extracting the raffinate of said extraction with liquid hydrogen fluoride or hydrofluoric acid.

An additional object of the invention is to produce highly refined lamp oils and fuel oils of superior quality with a minimum loss in oil and consumption of reagent materials.

Still another object of the invention is to produce petroleum products of the distillate type composed substantially of paraffin and naphthene type hydrocarbons (saturated hydrocarbons) from a high sulfur content asphalt base or mixed base crude oil source, without the production of large quantities of acid sludge waste and thus avoid the related problem of sludge disposal.

In the production of lamp oils or fuel oils from asphalt or mixed base crude petroleum oil the major refining problem is one of removal or separation of relatively large amounts of aromatic hydrocarbons and sulfur compounds to produce a product composed substantially of paraffin and naphthene type hydrocarbons. Previous methods of accomplishing this refinement employed large amounts of sulfuric acid at elevated temperatures to cause a series of chemical changes to occur in a portion of the unsaturated, paraffinic, naphthenic and aromatic hydrocarbons and the sulfur containing compounds. The products of these chemical reactions, being soluble selectively in the resultant acid sludge layer, were removed by separation of the same from the unreacted oil layer. The chief disadvantage of this method was in the chemical action which degraded valuable hydrocarbon materials, consumed large amounts of sulfuric acid and posed a serious problem of reagent recovery and sulfuric acid sludge disposal.

2

Another well-known method for refining petroleum oil distillates containing substantial amounts of unsaturated and aromatic type hydrocarbons and sulfur compounds is the sulfur dioxide extraction method in which a paraffinic raffinate is produced by selectively extracting the unsaturated, aromatic and sulfur-containing components of the stock. This method, however, does not completely or adequately separate the non-paraffinic and sulfur compounds from the paraffinic compounds desired in the lamp oils and fuel oils of this invention. Further treatment with sulfuric acid or fuming sulfuric acid has been applied to achieve more complete refinement. These finishing methods also involve considerable losses of desired hydrocarbons due to oxidation and sulfonation.

This difficulty appears to be due in part to the use of reagents containing sulfur in performing the finishing treatment. Sulfuric acid, fuming sulfuric acid, other acids of sulfur and oxides of sulfur introduce into the oil reaction products containing sulfur. Although the use of these reagents results in a net decrease in the natural sulfur content of the stocks treated, the sulfur containing products remaining in the finished oil are equally objectionable.

Small amounts of these residual impurities and reaction products may result in chimney deposits, crust formation on wicks and wick destruction in the case of lamp oils. In fuel oils, such as Diesel fuels, they cause corrosion, mineral deposits and plugging of the fuel injection system.

It has now been found that these difficulties are overcome and higher yields of finished lamp oils and distillate fuels of premium quality are obtained by employing a hydrofluoric acid treatment on the raffinates obtained from sulfur dioxide extraction. A petroleum oil distillate obtained from an asphalt or mixed base crude petroleum oil is first treated by an extraction with liquid sulfur dioxide at reduced temperatures in the range of about —40° F. to about +70° F., but preferably in the region from about 10° F. to about 30° F. where substantially all of the sulfur dioxide is in the liquid form. Sufficient sulfur dioxide is employed to extract a major portion of the undesirable components of the charge oil (aromatic and unsaturated hydrocarbons, sulfur compounds, nitrogen compounds, phenols, naphthenic acids, asphaltic substances, etc.) without extracting substantial amounts of the desirable components such as the paraffin hydrocarbons. The amount of sulfur dioxide used is determined by the stock being treated and the degree of refinement de-

sired. The treating conditions are chosen to allow a minimum amount of aromatic hydrocarbons, consistent with the permissible smoke tendency, to remain in the raffinate oil fraction of lamp oils.

The raffinate layer containing the desirable saturated hydrocarbons is separated from the extract layer and is freed of substantially all the dissolved sulfur dioxide by evaporation. This partially refined oil contains the sulfur compounds of the original charge which are the least susceptible to removal by sulfur dioxide, and also small amounts of sulfur compounds resulting from the sulfur dioxide extraction itself along with sulfur dioxide not removed by the evaporation step. If the partially refined oil goes to tankage before proceeding with the next step of refinement it is possible for a small but significant amount of oxygen to be absorbed. In order to avoid interfering effects of dissolved oxygen and sulfur dioxide in the final refining, the dissolved oxygen and sulfur dioxide are removed by distillation with reflux or by stripping prior to sending the partially refined oil to the next refining stage.

To completely refine this fraction a second extraction, employing liquid hydrofluoric acid or hydrogen fluoride, is performed whereby these residual impurities, consisting mainly of sulfur compounds, are reduced to an insignificant proportion without the removal of appreciable amounts of desirable hydrocarbons, or the introduction of additional sulfur compounds or impurities. The extraction with liquid hydrofluoric acid, which is performed in the proper manner to cooperate with the sulfur dioxide extraction in a combined refining process, is conducted at suitable temperatures and pressures and employing suitable proportions of hydrofluoric acid relative to the sulfur dioxide raffinate oil. The temperatures may be between about -50 and about 300° F. but conditions are usually chosen so that temperatures not far above nor below normal atmospheric values, namely, from about 30° F. to about 100° F., can be employed. The hydrofluoric acid used may be diluted with water to the extent of as much as about 20% by weight in the mixture. However, treating acid containing not less than 90% hydrogen fluoride by weight is preferred to complete the refinement of most SO₂ raffinate oil fractions. The hydrofluoric acid is used in sufficient amount to form a distinct liquid phase which will readily settle out to form a liquid hydrochloric acid extract layer separable from the major portion of original oil charge contained in the raffinate layer. The amount needed may vary with the content of residual impurities remaining after the SO₂ extraction and the amount of water in the hydrofluoric acid. For hydrofluoric acid containing about 99% hydrogen fluoride by weight an amount between about 5 and 200 percent by volume of the SO₂ raffinate oil is generally satisfactory, but in cases where the content of sulfur-containing compounds is high the amount of hydrofluoric acid may greatly exceed 200% by volume of the oil extracted. The hydrofluoric acid is removed from the raffinate layer by distillation with reflux and/or stripping and is thereby recovered for continuous use.

Although very little fluorine is introduced into the finished oil by the hydrofluoric acid treatment, objectionable amounts of fluorine may be readily reduced to negligible proportions in the oil by any suitable means such as passing the vaporized oil over lime or bauxite at elevated temperatures.

Catalytic defluorination using etched aluminum rings to defluorinate the oil vapor may also be used.

By the process just described the selective solvent effects of liquid sulfur dioxide and liquid hydrogen fluoride or hydrofluoric acid are combined to produce higher yields of more completely refined products (of extremely low sulfur content and controlled hydrocarbon type composition) than was possible by the processes described above. This result is achieved by choosing the sulfur dioxide extraction conditions so that all of the aromatic hydrocarbons are extracted except the small proportion that can be tolerated in the final lamp oil, for example, and then performing the hydrofluoric acid extraction under the conditions for optimum selective extraction of the residual sulfur compounds with minimum extraction of aromatic hydrocarbons. The extract oils resulting from both extractions are readily recovered by evaporation and stripping operations which at the same time recover the sulfur dioxide and the hydrofluoric acid solvents. The SO₂ extract oil is a valuable source of aromatic hydrocarbons and the HF extract oil contains sulfur compounds which are useful raw materials for the production of various chemicals such as odorants, perfumes, solvents, and lubricating oil additives.

The invention will now be more particularly described and illustrated in connection with the accompanying drawing which is a schematic flow diagram of a specific embodiment of the invention. Some auxiliary equipment such as condensers, reflux drums, exchangers, etc. which may be desirable or necessary for the operation of the process, and the need for which is obvious to anyone versed in the art, is not included in the diagram for the sake of simplicity in describing the process.

The charge oil is fed through line 1 into the bottom of SO₂ extractor 2 where the oil is mixed with liquid sulfur dioxide entering the SO₂ extractor at the top. The oil or raffinate phase, due to its lower density, moves toward the top of the extractor as the sulfur dioxide or extract phase drops to the bottom of the extractor where it is drawn off through line 3 leading to extract evaporator 4. The recovered sulfur dioxide is led back into SO₂ extractor 2 through line 25 and the SO₂ extract oil, composed chiefly of aromatic hydrocarbons, is withdrawn from the extract evaporator via line 6.

The raffinate phase is withdrawn from the top of SO₂ extractor 2 through line 7 and introduced into raffinate evaporator 8, where the major portion of sulfur dioxide is separated from the oil by distillation. The raffinate oil is passed to SO₂ stripper 10 through line 9 and the remnants of sulfur dioxide are stripped from the raffinate oil by passing an oxygen-free stripping medium, such as a gaseous or low-boiling hydrocarbon fraction, through the heated oil.

After withdrawal from SO₂ stripper 10, through line 11, the SO₂ raffinate oil is introduced into the bottom of HF extractor 12 where it is mixed with liquid hydrofluoric acid being fed into the top of the HF extractor. As in the sulfur dioxide extraction just described, the raffinate phase moves toward the top of the extractor and the extract phase settles to the bottom. The extract or hydrofluoric acid phase is withdrawn from HF extractor 12 via line 13 and is fed into HF regenerator 14. Hydrofluoric acid is recovered by distillation and

stripping in regenerator 14 and recycled to HF extractor 12 through line 18. Fresh hydrofluoric acid make-up freed of oxygen and sulfur compounds may be fed to the system through line 15. An oxygen-free stripping medium, such as a low-boiling liquid hydrocarbon fraction, is used. The HF extract oil, consisting of a high proportion of sulfur-containing compounds, is withdrawn through outlet 16.

The raffinate phase produced, which includes some of the stripping medium introduced into regenerator 14, is withdrawn through line 17 from the top of the extractor and fed to HF stripper 18 where the hydrogen fluoride and most of the stripping medium are separated from the raffinate oil by distillation under reflux and recycled to HF extractor 12 through lines 19 and 15. The bottoms from HF stripper 18 is fed

hydrofluoric acid extracted oil and the fuming sulfuric acid treated oil as well as the SO_2 raffinate oil.

Color stability values were determined by measuring the color of the sample with a Saybolt Chromometer after keeping the sample in an oven at 212° F. for 16 hours. To evaluate the burning characteristics of the samples A. S. T. M. lamp test method D-187 was used. Comparison to standard test results were obtained by comparing the burning qualities of the samples as determined by the lamp tests, with the burning qualities of a sample of high-grade lamp oil prepared from a paraffin base crude petroleum source, and chosen as a standard because of its excellent burning characteristics.

The data obtained in these tests are collected in the table below:

Inspections	SO ₂ Raffinate	Finished Oil	
		H ₂ SO ₄ Treated	HF Extracted
Gravity, ° A. P. I.	44.8	44.9	44.8
Sulfur, per cent	0.0082	0.0012	nil.
Color, Saybolt	+30	+30	+30
Color stability (16 hrs. at 212° F.)		+27	+30
48 Hour Lamp Test:			
Flame	OK (dropped $\frac{1}{4}$ "")	OK	OK
Wick	OK (medium-heavy crust)	OK	OK
Chimney	Bad	Just bad	OK
Comparison to standard		Below standard	Above standard

through line 20 into kerosene stripper 21 where the remaining hydrocarbon stripping medium is stripped from the treated oil with steam, the finished oil being withdrawn through outlet 22. The wet stripping medium is passed overhead.

Although counterflow through packed columns is shown in the extraction sections of the above illustration, other conventional means of contacting liquids such as mechanically driven agitators, circulating pumps, atomization of treating material into confined oil, etc., may be used with counterflow or conflow of liquid streams. Instead of continuous contacting, batch or combinations of batch and continuous treatments may be practiced by methods well known in the art. Accelerated methods of separating the mixed liquids, such as centrifuging, for example, may be applied with advantage in connection with some mixing apparatus.

Example

The following example illustrates some of the many advantages obtained as a result of practicing the present invention. A lamp oil stock derived from a California crude petroleum oil having a gravity of 40.3° A. P. I., and containing 0.040 percent sulfur was extracted at 25° F. with 70 percent by volume of sulfur dioxide based on the oil charged. The yield of SO₂ raffinate oil was 77.1 percent by volume of the charge. A portion of this raffinate oil was extracted at 70° F. with 50 percent of its own volume of hydrofluoric acid containing 99 percent by weight of hydrogen fluoride. A yield of 99 percent finished oil, based on the SO₂ raffinate charged, was obtained.

For purposes of comparison, a second portion of the SO₂ raffinate oil was treated with commercial sulfuric acid at 70° F. using the equivalent of 0.15 pound of 15 percent fuming sulfuric acid per gallon of oil. A yield of 96 percent by volume of acid treated oil was obtained.

Inspections and lamp tests were run on the

A comparison of the results obtained on the finished oil prepared by sulfur dioxide extraction followed by hydrofluoric acid extraction (HF extracted) with those obtained on the SO₂ raffinate shows the extremely low sulfur content, the excellent color stability, and the greatly improved burning characteristics of the hydrofluoric acid extracted finished oil. The fuming sulfuric acid treated finished oil, although better than the SO₂ raffinate oil, is not as high in quality as the HF extracted finished oil which is definitely superior with respect to color stability, sulfur content and burning characteristics. The use of sulfuric acid results in some sulfonation and even though there is a net reduction in sulfur, some equally objectionable sulfonation products may be left in the finished oil.

The absence of appreciable chemical action between the SO₂ raffinate oil and hydrofluoric acid accounts for the very high yield (99 percent based on the charge oil) obtained from the hydrofluoric acid extraction as compared to the lower yield (96 percent based on the charge oil) resulting from the fuming sulfuric acid treatment. The fluorine content of the hydrofluoric acid treated oil in the above example was found to be nil.

Since substantially no aromatic removal takes place during hydrofluoric acid extraction, the sulfur dioxide extraction preceding the same is performed under those conditions that will result in an SO₂ raffinate oil containing an aromatic content reduced to the desired degree. This concentration of aromatic hydrocarbons corresponds to the maximum aromatic content permitted in the hydrofluoric acid finished oil. Thus substantially all the aromatic hydrocarbons to be removed are separated during the sulfur dioxide extraction and can be readily recovered from the SO₂ extract by simple physical processes.

Sulfuric acid treatment of the SO₂ raffinate, on the other hand, always involves the sulfonation of some of the aromatic, paraffinic and naphthenic hydrocarbons which are lost in an acid sludge of relatively little value.

The combination of sulfur dioxide extraction (for the removal of the major portion of aromatic hydrocarbons and some of the sulfur compounds from the original hydrocarbon oil) with hydrofluoric acid extraction (for the purpose of removing the residual sulfur compounds) produces excellent results largely because of the high degree of selectivity that hydrofluoric acid shows toward the types of sulfur compounds remaining in the SO_2 raffinate oil. That these sulfur compounds may have a different distribution and composition than those contained in the original charge oil is illustrated by the greater selectivity exhibited by the liquid hydrofluoric acid toward the residual sulfur compounds in the SO_2 raffinate than toward the sulfur compounds in the virgin oil.

A Midway stock for the production of mineral seal oil was extracted with sulfur dioxide to produce an SO_2 raffinate. The original stock and three portions of the SO_2 raffinate were extracted with hydrofluoric acid by thoroughly mixing the oil and acid for 20 minutes and then settling and separating the two phases in each case. The sulfur contents of the HF raffinates and acid phases were determined and the ratio of the percent by weight of sulfur in the acid phase to that in the raffinate phase (distribution ratio) was calculated for each experiment. A high ratio indicates relative ease of removal of sulfur from the oil by the hydrofluoric acid. The data obtained in these experiments are tabulated below.

Charge	Temp., ° F.	Vol. of HF per vol. of oil	Per cent S by wt. in raffi- nate	Per cent S by wt. in acid phase	Distribu- tion Ratio
Original Stock...	100	0.55	0.15	1.03	6.87
SO_2 Raffinate...	100	0.11	0.086	1.78	20.7
Do.....	100	0.99	0.024	0.323	13.4
Do.....	30	0.10	0.083	1.82	21.9

The much higher distribution ratios obtained for the sulfur in extractions of the SO_2 raffinates, ranging from 13.4 to 21.9, compared to 6.87 obtained for the original stock, illustrate the greater effectiveness of hydrofluoric acid toward removal of sulfur compounds from the SO_2 raffinates than from the stock, and indicate that either the sulfur compounds in the SO_2 raffinates differ from those in the stock, or that the distribution of type of sulfur compounds in the SO_2 raffinates differs from that in the stock, or both.

While the character of the present invention has been described and exemplified in detail by way of illustration, it will be understood that the invention embraces such other variations and modifications as come within its spirit.

We claim:

1. A process of refining a hydrocarbon oil containing aromatic and non-aromatic hydrocarbons and sulfur compounds to obtain therefrom a high yield of a product of extremely low sulfur content and of controlled hydrocarbon type composition, comprising first extracting said hydrocarbon oil with liquid sulfur dioxide to remove the desired major amount of aromatic hydrocarbons therefrom, and subsequently extracting the raffinate obtained from the sulfur dioxide extraction with liquid hydrogen fluoride in the absence of added agents other than up to 20% water to remove sulfur compounds substantially completely therefrom without appreciably changing the minor aromatic content of said raffinate.

2. A process of refining a hydrocarbon oil containing aromatic and non-aromatic hydrocarbons and sulfur compounds to obtain therefrom a high

yield of a product of an extremely low sulfur content and of controlled hydrocarbon type composition, comprising first extracting said hydrocarbon oil with liquid sulfur dioxide to remove therefrom a desired major amount of aromatics and some of said sulfur compounds, leaving in the raffinate sulfur compounds which are more amenable to removal by liquid hydrogen fluoride than those in the hydrocarbon oil prior to liquid sulfur dioxide extraction, and subsequently extracting the raffinate obtained from said sulfur dioxide extraction with liquid hydrogen fluoride in the absence of added agents other than up to 10% water to remove the remaining sulfur compounds substantially completely therefrom without appreciably changing the minor aromatic content of said raffinate.

3. A process of refining a lamp oil stock containing aromatic and non-aromatic hydrocarbons and sulfur compounds to obtain therefrom a high yield of a lamp oil product of extremely low sulfur content and of controlled hydrocarbon type composition, comprising first extracting said lamp oil stock with liquid sulfur dioxide to remove therefrom the desired major amount of aromatic hydrocarbons and some of the sulfur compounds, leaving in the raffinate sulfur compounds which are more amenable to removal by liquid hydrogen fluoride than those in the original stock prior to liquid sulfur dioxide extraction and subsequently extracting the raffinate obtained

from the sulfur dioxide extraction with liquid hydrogen fluoride in the absence of added agents other than up to 20% water to remove the remaining sulfur compounds substantially completely therefrom without appreciably changing the minor aromatic content of said raffinate.

4. A process for refining lamp oil stocks which comprises extracting the stock with liquid sulfur dioxide to obtain an extract containing a fraction of the sulfur compounds contained in said stock and a major fraction of the aromatic compounds in said stock and a raffinate containing the remainder of the sulfur compounds of said stock, and also the sulfur compounds resulting from the contact of sulfur dioxide with the stock and aromatic compounds in amount slightly below the maximum consistent with permissible smoking tendency, and thereafter extracting the raffinate of the sulfur dioxide extraction step with hydrofluoric acid under conditions adapted to remove an extract substantially free of aromatic compounds and containing substantially all of the sulfur compounds present in said raffinate.

5. The method of obtaining from a sulfur containing petroleum distillate an extract consisting essentially of sulfur compounds which comprises extracting said distillate with liquid sulfur dioxide to remove in the extract a major fraction of the aromatic content of said distillate, and thereafter extracting the raffinate of the sulfur dioxide extraction step with concentrated hydrofluoric acid to yield an extract substantially free of aromatic compounds and consisting essentially of sulfur compounds.

6. The process as defined in claim 1 wherein the

sulfur dioxide extraction step is conducted at 10-30° F., and the hydrogen fluoride extraction step is conducted at 30-100° F., and water added to the hydrogen fluoride does not exceed 10% by weight of the water-hydrogen fluoride mixture.

7. The process as defined in claim 1 wherein the sulfur dioxide extraction step is conducted at 10-30° F., the hydrogen fluoride extraction step is conducted at 30-100° F., and the hydrogen fluoride employed is substantially anhydrous.

8. The process as defined in claim 4 wherein the sulfur dioxide extraction is conducted at 10-30° F., the raffinate of the sulfur dioxide extraction is extracted with aqueous hydrofluoric acid containing at least 90% by weight of hydrogen fluoride, and the hydrofluoric acid treating step is conducted at 30-100° F.
